CLAIM

I claim the ornamental design for the “flying disc for playing disc golf,” as shown and described.

DESCRIPTION

FIG. 1 is a top plan view of a flying disc for playing disc golf showing my new design;

FIG. 2 is a cross sectional view taken along line 2—2 of FIG. 1;

FIG. 3 is a bottom plan view thereof;

FIG. 4 is a front perspective view thereof; and,

FIG. 5 is a front elevation view thereof. The rear, left and right elevation views are identical to the front view shown.
